Primary Examiner—Bernard Ansher*Assistant Examiner*—R. Barkai*Attorney, Agent, or Firm*—Trexler, Bushnell, Giangiorgi & Blackstone, Ltd.[57] **CLAIM**

The ornamental design for a scissor handle, as shown and described.

DESCRIPTION

FIG. 1 is a left side elevational view of a scissor handle showing our new design, and further showing coupled scissor blade fragments in phantom illustration;

FIG. 2 is a right side elevational view of the scissor handle in FIG. 1 (omitting the phantom illustration therefrom);

FIG. 3 is a top plan view thereof;

FIG. 4 is a bottom plan view thereof;

FIG. 5 is a front elevational view thereof; and,

FIG. 6 is a rear elevational view thereof.
